UNITED STATES PATENT OFFICE

CHARLES LAURENCE BURDICK, OF LONDON, ENGLAND

CHANGE-PAYING DEVICE

Application filed March 15, 1928, Serial No. 261,998, and in Great Britain April 12, 1927.

Coin paying machines in which the coins ejected represent the change from a given tender in respect of a sale of the value of the keys struck have already been proposed.

5 Machines of this type have also been proposed which were capable of giving the correct change in respect of more than one tender.

10 The range of operation possessed by such machines has, however, been limited to two or three tenders, not only from theoretical reasons based on systems of coinage, but also by reason of considerations of bulk and complexity, and the modes of operation proposed have been unsuitable for operation over the complete range of tenders and sales possible within the limits, for example, of British coinage up to tenders of £1.

15 The present invention has for its object to provide a change-paying machine of the subtracting type of practicable bulk and complexity and capable of operating in response to a simple intellectual rule on the part of the operator in respect of any tender up to a high denomination such as £1. and in respect of any sale down to the smallest coin such as a farthing, i. e. to provide a "universal" change-paying machine.

20 It is therefore an object of the present invention to provide a machine of the subtracting type in which a single tender stop is applicable in the case of more than one tender.

25 It is a further object of the invention to provide means to set the machine to give correct change in respect of a multitude of tenders covering the ranges between the values of any two tender stops.

30 In accordance with the invention the machine includes two keyboards, one comprising a set of keys hereinafter referred to as "stops" for operation in accordance with the tender, and the other comprising a set of keys to be operated in accordance with the sale; the machine is generally worked by the operator (except in the case of a very small number of unusual tenders) according to the simple rule that the tender stop required to be operated is that of the smallest coin or plurality of like coins in the tender.

35 The machine is thus designed in accord-

ance with the usual fact that change given from any tender is less than the smallest coin tendered, otherwise the smallest coin should be handed back to the purchaser and the payment taken from the remaining tender.

40 It is thus a further object of the invention to provide means to set the machine to give correct change in respect of a given tender on actuation of the tender stop for the smallest of a plurality of coins tendered, and of keys to the amount of the sale.

45 Further objects include the provision of means to include a note in the change ejected, and means whereby the machine is combined with a cash registering mechanism, the change-paying mechanism being normally disconnected therefrom but being automatically connected operatively therewith when any tender stop is actuated.

50 These and other important and diverse objects will be made clear in the following description and set out in the appendant claims.

55 The machine will be described primarily with reference to British coinage, a note being added concerning its adaptation to United States of America coinage at the end of this specification.

60 In accordance with the preferred form of the invention the whole range of coinage is regarded as comprising four denominations, for example, pounds, shillings, pence and farthings, and the sales keys when actuated according to their simplest mode of action are arranged to set ejectors to deliver change from a unit of the next higher denomination. For example the farthings keys are set to deliver the complementary number of farthings to make up a penny, the pence keys the correct change from a shilling and the shillings keys the correct change from a pound.

65 Specific keys are not provided for 0 pence, nor 0 shillings, but to cover the maximum range where, for example, a pound is tendered for a farthing sale, "auto-bars" are provided according to which when a farthings sales key is operated and no pence key is operated, an additional 11 pence is thrown out by the ejectors, and when a pound tender stop is operated but no shillings sales key

is depressed, 19 shillings is thrown out by the ejectors.

Excluding for a moment tenders which include one or more half-crowns, it is thus comparatively simple for example when the tender is a penny or any number of shillings plus a penny, (in which circumstances only the penny tender stop is operated), to arrange that the ejectors in respect of coins higher than a penny are inhibited, so that whatever sales keys (to the full amount of the sale) are depressed, only the farthings sales key operates to throw out the change from the odd penny in the tender. Similarly, where the smallest coin tendered is one shilling, all the sales keys higher than pence are inoperative and the pence keys, or the pence and the farthings keys throw out the change from the shilling.

At this point, however, it should be noted that if the depression of a sales key for a penny throws out 11 pence and for a farthing throws out three farthings, the operation of both these keys together will throw out $11\frac{3}{4}$ d. instead of $10\frac{3}{4}$ d. which is the normal change for $1\frac{1}{4}$ d. from a shilling; and in such case I provide automatic means whereby when sales keys of two denominations are operated together a unit (1 penny in the case considered) is eliminated from the change. Obviously a similar requirement must be met whereby a shilling is eliminated when a shillings key and a pence key, or a shillings key and a farthings key, are operated together.

A tender which includes 6d. or 3d. as the smallest coin is naturally provided for by eliminating 6d. or 9d. from the normal action of the pence and farthings sales keys.

Where the smallest coin tendered is a florin (2/-), if the sales keys actuated include an even number of shillings or no shilling at all, an auto-bar throws out a shilling in addition to the normal change of the pence sales keys which function in their usual manner.

Turning now to tenders which include half-crowns, I provide two tender stops, one for even numbers of half-crowns and the other for odd numbers of half-crowns. The tender of even half-crowns is a tender of 5/-, 10/-, 15/-, or 20/-. The sales amount must lie between 2/- and 4/-, or 7/- and 9/-, or 12/- and 14/-, or 17/- and 19/-; plus possible pence and farthings, and the change must lie in each of the four cases considered between $2\frac{5}{8}$ d. and $\frac{1}{4}$ d.

In the case of a tender of even half-crowns, the machine is arranged that when the sales keys operated lie between the ranges mentioned, the action of the coin tubes holding the coins of higher denomination than one shilling is inhibited in which case the ejectors of the remaining tubes throw out three separate shilling pieces, two shillings or one shilling, being the difference in each case between the amount of the shillings sales key

depressed and the multiple of 5/- comprised in the tender, a shilling of this amount of change being eliminated in the ordinary way therefrom when a pence or farthings key is also actuated. This operation is made possible by suitable selection of the constituent coins making up the maximum change of 19/- in the shillings denomination.

Similarly, the tender stop for the odd half-crowns connotes a tender of 2/6d., 7/6d., 12/6d., or 17/6d. As the pence sales keys normally give the correct change for 1/-, the odd half-crown tender stop is arranged to work an auto-bar which normally throws out a supplementary shilling and sixpence. Thus when a pence or farthings sales key is operated; or a 1/-, 6/-, 11/- or 16/- sales key without pence, the correct change is thrown out comprising 1/6d. added to the normal change from 1/- which is ejected by the pence keys, or 1/6d. alone. If, however, a pence or farthings sales key is depressed in conjunction with the 1/-, 6/-, 11/- or 16/- sales key, a shilling of the 1/6d. otherwise thrown out by the auto-bar is inhibited, and when the sales amount is 2/-, 7/-, 12/- or 17/- plus a fraction of pence or farthings, the remaining 6d. of the amount thrown out by the auto-bar and a further 6d. from the normal change of the pence or farthings key is inhibited.

Thus the machine is enabled to work in accordance with the usual combinations of coins offered in tender on the basis that a single tender stop is depressed corresponding to the amount of the lowest coin offered in tender.

The above gives an outline of the general nature of the invention, and I will now describe a specific embodiment.

One embodiment of the invention is illustrated by way of example in the accompanying drawings in which

Fig. 1 shows a side view, and Fig. 2 a plan of a complete machine,

Fig. 3 is a sectional side view showing the ejector mechanism and means to connect the sales keys with the ejector devices.

Fig. 4 is a sectional plan of the ejector mechanism illustrated in Fig. 3.

Fig. 5 is a sectional plan beneath the sales keys stems, and Fig. 6 is a sectional plan on a higher plane than Fig. 5, and illustrating inhibitor mechanism operated by the tender stops.

Fig. 7 is an elevation showing re-setting mechanism, and

Fig. 8 is an elevation of certain of the mechanisms illustrated in Figs. 5 and 6.

Figs. 9 to 23, and Fig. 26 show various views of details.

Fig. 24 shows the arrangement and principal functions of the sales keys.

Fig. 25 shows particulars of the coins

ejected as change when the various sales keys are operated, and

Fig. 27 shows an alternative arrangement of sales keys in respect of American coinage.

Turning first to Figs. 1, 2 and 3, the machine comprises a series of tender stops M and a set of sales keys N , there being a separate key for each integral number of pounds, shillings, pence and farthings up to £1. The 10 coins are carried in two sets of coin tubes O , O^1 , the first set holding coins up to the value of 6d., and the second set higher denominations. In addition, a set of clips O^2 , Fig. 3, is provided for 10/- notes. The coin tubes 15 are telescopic and the coins are urged upwardly in the tubes by spring means, the uppermost coin being ejected when appropriate by means of generally similar ejector levers P , shown separately at Fig. 16, which operate 20 horizontally-arranged ejectors to throw the coins into a central chute Q . The coins are held in by hinged stop plates R which carry pivoted stops S adapted to fall and prevent movement of the ejector levers P 25 when the last coin has been ejected, or if the coins jamb and are not pushed up by the springs so that the lug S^1 carried by the stop S is no longer supported thereby.

As shown more particularly in Fig. 3, the 30 levers P are mounted on transverse shafts 10, and have downwardly extending tails such as P^1 articulated to the levers by pivots 11 running transversely to the shaft 10 and normally held in alignment with the levers 35 by springs 12. The tails are adapted to be engaged by hook-shaped members which may be termed "ejector hooks" each controlled by a spring of which one is shown at 13c in Fig. 4, and loosely articulated at 14 to two 40 series of links 15 corresponding to the two rows of ejectors required by the two rows of coin tubes O , O^1 , the links being rigid with two shafts 16, 17 geared together by the gears 18, 19, and operable by the handle 45 20 to move the ejector hooks outwardly of the rows. The positively-actuating faces 13a of the ejector hooks 13 are normally clear of the tails P^1 as shown in Fig. 4, but owing to the loose articulation of the ejector hooks 50 with the links 15 they are capable of being rocked to the right in Fig. 4 (as shown in dotted lines in the case of the left hand hooks) to lie behind the tails on the actuation of their respective sales keys N after the latter 55 have been armed by operation of a tender stop. Return lugs 13b are provided on the hooks 13.

The coupling of the sales keys which are normally disconnected from the ejector mechanism is effected by one of two pairs of rocking links 30, 31, Fig. 3, mounted respectively on concentric shafts 32, 33; and one or both shafts is adapted to be rocked on the operation of a tender stop M by a pivoted lever 60 65 M^1 engaging with a bar 34, or 34a, Fig. 4,

attached to the shafts 32, 33 respectively. Each tender stop operates a separate lever such as M' , and each lever engages one of the bars 34, 34a. Tender stops for £1., 10/- and even half-crowns arm all the sales keys, 70 but the other tender stops only arm the pence and farthings keys.

It will be seen by comparing Fig. 2 and Fig. 4 that bar 34 is arranged opposite the right hand six stops and bar 34a opposite the £1., 10/- and even half-crowns stops. If one of the latter is actuated, its lever rocks both shafts, but when the other stops are actuated only shaft 32 is rocked.

The coupling of the sales keys is effected by means of two pairs of sliding bars T , T^1 , the bars T^1 being partly offset vertically and lying partly over the bars T as shown in Fig. 3. The bars T and T^1 are both moved by links 31 when the outer shaft 33 is rocked but the bars T^1 only are moved by links 30 when the inner shaft 32 is rocked.

The bars carry inclined slots 35, Fig. 4, in which are arranged pins 36 carried by four sliding rods 37 on which are mounted cam-shaped members 38, of which one is provided in conjunction with each sales key. The cam-shaped members 38 are rocked by pins 39 mounted on the rods N^2 , N^3 , N^4 of the sales keys N whenever the latter are depressed. Normally the cam-shaped members 38 rock idly, the lower ends of the rods N^2 , N^3 , N^4 merely actuating cash register mechanism, but when the sales keys are required to be coupled, bars T or T^1 shift the corresponding cams 38 to the right in Fig. 4, and the cams so shifted are then positioned opposite finger bars 50 of which one is provided in conjunction with each sales key, and the depression of a sales key and rocking of a cam 38 will then cause the corresponding finger bar to be moved to the right in Fig. 3.

The finger bars 50 run from front to rear of the machine and each finger bar is coupled to a selector bar running transversely of the machine by means of an inclined lug 51, Fig. 17, struck from the upper edge of the finger bar and engaging between two lugs 52, Fig. 18, formed in the lower edge of the selector bar. The whole series of selector bars is indicated at U , U^1 , Fig. 4, and they are moved transversely by the lugs 51 when bars 50 are operated to perform the usual function of selector bars in coin-paying machines—in this case by rocking the appropriate ejector hooks 13 to the right in Fig. 4. For this purpose they are provided with slots 52a, Fig. 18, in their upper edges which receive all the ejector hooks corresponding to each particular series U or U^1 , the left hand wall of the slot being close to the left hand face of the ejector hook in the case of those ejector hooks which has a particular selector bar is designed to operate.

As already explained, the actuation of a coupled sales key operates normally to eject the complement of the sales amount from unity of the next higher denomination. Thus the selector bar operated by the 19/- sales key rocks ejector hooks corresponding to 1/- of the coin tubes, and the 1/- sales key operates a selector bar which rocks hooks corresponding to 19/- of the coin tubes. Similarly, the penny sales key operates ejector hooks corresponding to 11d. of the coin tubes and the farthing sales keys operate the complement of a penny.

In order to meet the case of a higher tender such as a pound for a small sale such as a farthing without providing for the operation of special sales keys for 0 shillings and 0 pence, automatic means are provided for ejecting supplementary sums of 19/- and 11d. in case of need. In this connection, I provide for the ejection of supplementary 19/- from the £1. tender stop and for the supplementary ejection of 11d. from the farthings sales keys.

The tender stop for £1. is shown at the left hand end of the series in Fig. 2, and its lever M^{1*} bears against a pin 50M in a bar 50a, Figs. 3 and 4, which is generally similar to and lies with the series of finger bars 50 operated by the sales keys. The bar 50a operates a selector bar which I call an "auto-bar" in the series U^1 so that whenever the tender stop for £1. is depressed the aforesaid 19/- auto-bar deflects into their operative positions ejector hooks 13 corresponding to 19/- of change.

The supplementary 11d. thrown out by the farthings keys is provided for by mechanism which I call grid F illustrated in Figs. 5, 7 and 9. As here shown, grid F comprises three arms 62, 63, 64 terminating in blocks which lie below the three farthings sales keys respectively, but are set a little to one side in normal position of the machine. The three arms are rigid with a shaft 65 capable of sliding to the left hand in Fig. 5, to the position shown in dotted lines, and the shaft is so moved to the left by means of a pin 66 lying in an inclined slot 67 formed by a spring member 68 carried by a sliding bar 69 adapted to be moved downwardly in Fig. 5 whenever any tender stop is depressed, by means of lever 70, Fig. 7, solid with the shaft 32. A transverse slot 67a leads from the upper end of slot 67 and communicates with a return slot 67b for a purpose to be described.

The grid F, however, is normally in inoperative position in order to leave the farthings sales keys without effect on the change-giving mechanism when the device is being used solely as a cash register.

When grid F is in the operative position shown in dotted lines in Fig. 5 and any farthings key is depressed, the shaft 65 is rocked

and links 72, 73, 74 operate a bar 50b, similar to the finger bars, which operates an auto-bar in the series of selector bars U to deflect ejector hooks corresponding to 11d. of the coin tubes. Thus if a pound is tendered for a sale of less than a penny the first auto-bar will operate ejector hooks for 19/-, the second auto-bar ejector hooks for 11d. and the farthings key will operate ejector hooks for its normal change from 1 penny.

As the auto-bar for 19/- is to operate only in the case of a sale including no complete shillings, it requires to be unset if a shilling sales key is depressed. This is provided for by cutting in the bottom of bar 50a, shown in Fig. 3, a slot 50c, which is shown dotted in Fig. 7, as the bar for 19/- lies exactly behind the bar 50b for automatic 11d. which is there illustrated in full elevation. The slot cooperates with a pin 50h carried by a bar 50k at the top of a rocking lever 50d linked to a further lever 50e solid with a shaft 75. The shaft 75 carries a second lever 50e, Fig. 5, at its opposite end, and between these two levers are arranged two bars 50g which lie under the two rows of shilling sales keys. When the bar 50a is moved forward by the pound tender stop, the bars 50g are raised to the position shown in dotted lines in Fig. 7 where they lie immediately beneath the lower ends of the shilling sales key rods N^2 . Thus if any of the shilling sales keys are thereafter depressed, the levers 50e will be rocked to their lower position, and the bar 50a will be returned by pin 50h to its inoperative position and will un-set the 19/- auto-bar. This unsetting mechanism I call grid H.

The unsetting of grid F (which when set is liable to actuate the 11d. auto-bar) is effected by apparatus which I call grid G comprising a bar 80, Fig. 5, arranged beneath the lower ends of the pence key stems N^3 and carried by arms 81 rocking about a shaft 82 under the control of a spring 83. The end of the bar 80 nearest to grid F carries a downwardly-extending cam 84, Figs. 5, 7 and 9, and when the bar 80 is depressed by any of the pence finger keys the cam 84 slides shaft 65 of grid F back to its unset position, this being rendered possible by means of transverse slot 67a leading out of slot 67 even though bar 69 (which is set by operation of any of the tender stops) remains in the set position. The pence stems N^3 operate grid G the moment they are depressed, the corresponding initial movement of the farthings stems being idle for the necessary period.

In order that when for example a pence and a farthings sales key require to be depressed together, a penny shall be eliminated from the sum of the normal change thrown out by a pence sales key and by a farthings sales key. If, for example, a sale is for 1½d. and if the penny sales key sets ejectors to throw out 11d. and the halfpenny sales key

an ejector to throw a $\frac{1}{2}$ d. a penny must be eliminated for the combined actions to throw out $10\frac{1}{2}$ d. instead of the sum of the amounts noted, and the mechanism for this feature will now be described.

The sales keys stems N^2 , N^3 , N^4 of the shillings, pence and farthings keys respectively are each provided with cam-faced blocks n , Fig. 10, having inclined faces n^1 on opposite sides, and the rows of keys are arranged between spring-controlled rods 90, 91, 92, 93, 94, 95, 96 capable of sliding laterally of the machine through holes in end plates as clearly shown in Fig. 6.

Rod 96 carries three lugs or rollers 96a adapted to be engaged by the cam faces n^1 of farthings keys N^4 so that the rod is moved to the left in Fig. 6 when any farthings key is depressed. Similarly, rod 94 is adapted to be moved to the right when any of the pence sales keys is depressed. Articulated to rod 96 is a triangular member which I call rocker C, the member having an abutment face C^1 adapted to be engaged by a pin 94b on rod 94. Articulated to the third corner of rocker C is a rod 97 extending to the rear of the machine and articulated through a bell-crank lever to a spring-controlled inhibitor finger 98 lying adjacent the tail P^{1x} Fig. 6, of the ejector lever operating with one of the penny coin tubes. If rod 96 is moved to the left in Fig. 6 by the depression of a farthings sales key, the joints of rocker C are sufficiently loose for no operative action to be made by inhibitor finger 98; but if simultaneously with the movement of rod 96, rod 94 also moves to the right by the simultaneous depression of a pence finger key, stud 94b will engage the abutment face C^1 of rocker C which will be operatively rocked and will cause inhibitor finger 98 to rock the tail P^{1x} of the ejector lever P of one of the penny coin tubes away from the operative face 13a of the corresponding ejector hook, Fig. 4, so that although the ejector hook remains set it cannot operate the ejector lever when actuated by the handle 20 as will be later described.

Rocker B, Fig. 6, operates in a similar manner through bars 97a, 97b and inhibitor finger 122 to eliminate a shilling by rendering inoperative the ejector lever P^{1n} of a shilling coin tube when rod 96 is moved simultaneously with either of rods 91 or 93 which are actuated by the shillings sales keys in a manner similar to the operation of the rod 94, and which carry studs 91b, 93b respectively for the purpose of rocking rocker B.

Rocker A operates in similar manner, to eliminate a shilling when a pence sales key and a shillings sales are depressed together. It is articulated to rod 95 which is moved to the left by any of the lugs 95a and is operated by studs 91b and 93b as in the case of rocker B. Rockers A and B operate on the same

ejector lever tail P^{1n} so that when both rockers move, only one shilling is eliminated.

The arrangement of the tender stops and their general function is illustrated in Fig. 24.

It has already been noted that the depression of any of the three higher value tender stops will couple all the finger bars by means of the bars T, T^1 but the operation of any of the remaining tender stops will only couple the finger bars for the pence and farthings keys through the movement solely of the bars T^1 .

On depressing the £1. tender stop, therefore, all the sales keys are operatively coupled and the auto-bar is operated to set ejector hooks for $19\frac{1}{2}$ — change. Similarly the $10\frac{1}{2}$ — tender stop arms all sales keys and operates an auto-bar to set ejector hooks. It is however, obviously necessary to inhibit $10\frac{1}{2}$ — from the change ejected in the ordinary way by the finger keys, and for this purpose the $10\frac{1}{2}$ — tender stop is coupled to an inhibitor bar 100, Figs. 6 and 13, having a lug 101 which operates to deflect the tail P^{1m} of the ejector lever connected with the $10\frac{1}{2}$ — note rack. The coupling comprises a stud 102 on the inhibitor bar working in an inclined slot 103 in a rod 104 carrying a pin 105, Fig. 8, adapted to be engaged by the tender stop lever.

Operation of tender stop for $10\frac{1}{2}$ — therefore moves rod 104 upwardly in Fig. 6, and inhibitor bar 100 to the right so that the lug 101 deflects the tail P^{1m} of the ejector lever for the note rack to the right away from the operative face 13a of the ejector hook.

Depression of the even half-crowns tender stop arms all the sales keys and inhibits all ejector levers for values over $1\frac{1}{2}$ —. This is effected through the rod 110 operated similarly to rod 104 and an inhibitor bar 116, Fig. 13, which lies below inhibitor bar 100 in Fig. 6, and includes lugs, one of which lies under lug 101 to inhibit the $10\frac{1}{2}$ — note rack, and lugs 112, 113, 114, 115 to inhibit two $2\frac{1}{2}$ — coin ejectors and two half-crown coin ejectors respectively.

The arrangement of combinations of coins to make up the maximum change in shillings from a pound tender is illustrated in Fig. 25, and the inhibition of the higher values of the coin tubes has the effect of leaving only the three $1\frac{1}{2}$ — tubes capable of being operated when the sales keys shown opposite to them in the left hand column are depressed.

The odd half-crowns tender stop operates a lever M^{1m} shown separately in Fig. 15, and carrying an attachment 117 so that two auto-bars may be simultaneously operated to set ejector hooks to deliver a shilling and a six-pence automatically. The operation of this mechanism is similar to the operation of the auto-bar for setting ejector hooks for $19\frac{1}{2}$ — operated from the pound tender stop as already described. As, however, the tender stop for the odd half-crowns and for lower

denominations only couples the pence and farthings sales keys, it is not necessary to provide this stop with an inhibitor to cut out the higher values of the coin tubes since these fail to be operatively connected to the higher values of the sales keys. This tender stop also sets the rod 120 having two cam-faced lugs 121 adapted when it is moved upwardly in Fig. 6 by the depression of the stop to engage the sliding bars 90, 92 through studs 121a and 121b and move them over to the right in Fig. 6.

The stems of the 1/-, 6/- and 11/- and 16/- sales keys which can be identified in Fig. 2 carry additional cams n^3 (see Fig. 11 which shows a rear view) which have similar faces to the faces n^1 of cams n . These cams n^3 are normally clear of rollers 90a, 92a carried by bars 90, 92 and can be depressed without affecting bars 90, 92, but if bars 90, 92 have first been set one step to the right by rod 120, depression of cams n^3 will move the corresponding bar 90 or 92 a second step to the right in Fig. 6, in which circumstances a lug 90b or 92b will come up against an abutment face of rockers E, E¹ which are similar in arrangement and function to rockers A, B and are articulated to rods 95, 96 respectively and operate an inhibitor finger 122a for one of the shilling tubes. Thus if the amount of the sale includes either 1/-, 6/-, 11/- or 16/- together with pence or farthings, the ejection of 1/- is automatically inhibited.

Similarly, the 2/-, 7/-, 12/- and 17/- sales keys carry cams n^4 , Figs. 12 and 19 which have twice the throw of cams n^3 and cause the inhibition of a shilling by operation of rockers E or E¹ by their own action and without the additional action of either of bars 95, 96. If bars 95, 96 actuated by the pence or farthings keys are operated conjointly with the operation of cams n^4 , rockers E, E¹ have a longer stroke and inhibitor fingers 123 actuated by a bell-crank lever 97, and link 97" inhibit the two sixpenny coin tubes in addition to the inhibition of the 1/- tube already described. The initial stroke of rockers E or E¹ is not transmitted to the fingers 123 by reason of the elongated slot illustrated in link 97d.

When the two-shilling tender stop is depressed an auto-bar similar to those already described is moved to set an ejector hook for a shilling. In addition to this auto-bar, a second auto-bar is adapted to arm ejectors for a further automatic delivery of a shilling when a sales key for an even number of shillings is thereafter depressed. This is effected by a mechanism which I call grid J in Figs. 6 and 8. Grid J generally resembles the mechanism for upsetting the 19/- auto-bar. It comprises two arms 130 carrying two transverse rods 131, 132 provided with lugs 133, 134 at spaced intervals along

their lengths. The arms 130 are spaced by a sleeve 135 sliding on shaft 75 and carrying a pin 136 engaged in an inclined slot in a bar 137 linked to a rocking lever 50n, articulated to a bar 50m which actuates the first shilling auto-bar just referred to. The arrangement is such that when the florin tender stop is depressed, the bar 137 moves downward in Fig. 6 and sets the sleeve 135 over to the right so that the lugs 133 and 134 are then positioned below the sales keys for even numbers of shillings. When any of these keys is thereafter depressed, the lugs 133, 134 are caught by special abutments 138 on the bottom ends of the stems of the "even shillings" sales keys, and the levers 130 are rocked, in which case a second auto-bar is operated through links 139, 140 to set the ejector hook for a second shilling tube. This adds the shilling that will be eliminated by rockers A or B.

After the operation of the tender stops, the sales keys setting the ejector hooks, the auto-bars and the various inhibitors, it will be realized that only those tails of ejector levers P remain engaged with the operative faces 13a of the ejector hooks in respect of such coin tubes as are required to eject the correct change. The lever 20 is then actuated and by means of gears 18, 19 all the ejector hooks are moved outwardly from the middle recess Q, and thus ejector levers which remain in operative engagement with their ejector hooks eject the appropriate change.

The delivery of 10/- notes from the note rack is effected as follows.

The note rack, Fig. 3, carries a series of clips O² and is held so that the uppermost loaded clip O¹² lies opposite a specially shaped ejector O¹³ having a bifurcated end to straddle the note rack. The rack is held up by a pair of pawls O⁴, O⁵, the pawl O⁴ being attached to a bell-crank lever O⁶ pivoted at O⁷ to a bracket O⁸ to which the pawl O⁵ is also pivoted. The tail of the bell-crank lever lies within a slot at the upper end of the ejector lever P and is so arranged that as the lever rocks on its operative stroke, the bell-crank lever O⁶ is rotated in a clockwise sense and the pawl O⁴ is moved downwardly one tooth of the note rack, the latter being meantime held stationary by pawl O⁵. The note in the uppermost clip is at the same time ejected. On the return stroke of the lever P, the bell-crank lever O⁶ is rocked in the opposite direction and the pawl O⁴ moves upwardly and lifts the rack by the amount of one tooth so that the next loaded clip is in the position for ejection. The ejector O¹³ is loosely pivoted to the lever P so that it can rock upwardly under the engagement of the next rising note, the top of the casing being shaped to allow this movement with the necessary clearance. The

5 pawls are adapted to be rocked away from the rack for re-filling by means of a spring-controlled rod O^9 having a bifurcated end engaging lugs on the tails of the pawls and adapted to be actuated by an external knob O^{10} .

From what has been said it will be appreciated that the following features remain constant in any operation of the machine.

10 (1) The sales keys when coupled set ejector hooks corresponding to amounts representing the differences between the value of the individual sales key operated and the unit of the next higher denomination of coinage.

15 (2) Whenever a shillings sales key is actuated simultaneously with a pence or farthings sales key, rockers A or B act to eliminate a shilling, and whenever a pence sales key is operated simultaneously with a farthings key, rocker C acts to eliminate a penny.

We will now consider the operation of the machine under various tenders.

20 25 £1. tender.—The delivery of change exceeding 19/11d. has already been described. In the case of a penny tender, grid G renders grid F inoperative; 19/- is delivered by the auto-bar operated by the tender stop and 11d. is delivered naturally by the penny sales key. If a sale is for 1½d. the action is the same, except that rocker C eliminates a penny from the combined effects of the penny and ½d. sales keys. If the sale is for 1/- grid H unsets the 19/- auto-bar and the sales key ejects the 19/- normally, and so on.

30 35 40 45 50 55 5/—tender.—The action is similar to that in respect of a £1. tender except that the auto-bar which operates for sales of less than a shilling naturally sets ejectors for 9/-, and that in respect of sales for more than a shilling, the tender stop inhibits 10/- from the normal change in the sales keys.

The automatic unseting of the auto-bar for 9/- is effected by a pin similar to pin 50h and carried by bar 50k, and is actuated by grid H in the manner already described.

Even half-crowns.—On turning to Fig. 25 it will be seen that when bar 110 inhibits the ejectors of all coin tubes for greater values than a shilling, the following result will obtain.

2/— sales key will set ejectors for 3/—
3/— sales key will set ejectors for 2/—
4/— sales key will set ejectors for 1/—
7/— sales key will set ejectors for 3/—
8/— sales key will set ejectors for 2/—
9/— sales key will set ejectors for 1/—

60 65 and so on. Assuming a sale of 2/6½d. from a tender of two half-crowns, the 2/— finger key sets ejector hooks for 3/—, the 6d. finger key sets ejector hooks for 6d. and the ½d. finger key sets an ejector hook for ½d., as grid G operates and eliminates the action of

grid F, so that the additional 11d. set by the farthings keys when no pence are included in the sales amount is inoperative. Rocker C eliminates a penny and rockers A and B whose actions are superimposed and are not additive eliminate a shilling, giving the resultant correct change of 2/5½d. If the sale is 3/— it will be seen from Fig. 25 that the 3/— finger key delivers 2/— which is correct. If the sale is 3/3d. the finger key for 3/— sets ejector hooks for 2/— and the finger key for 3d. ejector hooks for 9d., rocker A eliminating a shilling from the combined actions of the two finger keys. The result is similar for other tenders of even half-crowns and sales which do not require change exceeding 2/5¾d.

Odd half-crowns.—For sales of less than 1/— the appropriate auto-bar delivers 1/6 and the pence and farthings keys deliver their natural change from a shilling, which added to the 1/6d. gives the correct change from a single half-crown.

For sales requiring less than 1/6 change but more than 6d., either the 1/—, 6/—, 11/— or 16/— finger key must be operated together with a pence or farthing key. When this occurs, cam n^3 operates together with rod 95 so that rocker E eliminates 1/— and the pence and farthings keys throw out their usual change which is added to the remaining 6d. of the auto-bar.

When the change required is exactly 6d., i. e. a sale of 2/—, 7/—, 12/— or 17/—, rocker E¹ operates with a short stroke and eliminates a shilling from the action of the auto-bar. Whenever the change required is less than 6d., rocker E¹ acts with its longer stroke and eliminates first the 1/— of the auto-bar, then the 6d. of the auto-bar and a second 6d. which is thus deducted from the normal change thrown out by the pence or farthings keys.

2/— tender.—For one coin tendered and a sale of less than a 1/—, 1/— is thrown out by the auto-bar and the pence and farthings keys deliver their usual change.

For sales of 1/—plus pence or farthings, 1/— is thrown out by the auto-bar and the pence and farthings keys throw out their usual change with the penny eliminated. As, however, a shilling sales key and a pence and/or farthings sales key are depressed together, rocker A or B operates and eliminates a shilling from the above total leaving the correct change.

For sales amounting to an even number of shillings plus pence or farthings requiring change of 1/— plus coppers, the auto-bar sets an ejector for 1/— and grid J acts to set an ejector for a further 1/—. Again the pence and farthings keys throw out their usual change and rocker A or B deducts a shilling from the two already provided.

In view of the above explanations, the action in the case of shilling or penny tenders

requires no further explanation. In the case of tenders of 6d., 3d. or 1d., the stops actuate through inhibitor rods 110a, 110b and 110c respectively the three inhibitor bars which are illustrated in Fig. 14, and inhibit the two 6d. tubes, the two 6d. tubes and the 3d. tube, and all the tubes for 1d. and more, respectively. Their action is similar to that of the inhibitor bars 104 and 110 and needs no further description.

The resetting of the parts is effected as follows.

The finger bars 50 are provided with an upper slot 150, Fig. 17, and a rod 151, Fig. 7 lies in this slot across the machine. The rod 151 is carried in a pair of arms 152 Figs. 1, 5 and 7, the rear ends of which are provided with an L-shaped slot having a horizontal portion 153 and a downwardly-extending portion 154, the rear end of the arm being drawn upwardly by a spring 155. A pin 156 carried by a link 157 rigid with shaft 17 is engaged in the slot. The rear end of the arm 152 is provided with a cam-shaped lug 158 and a roller 159 adapted to be engaged with said lug is mounted in a bracket 160 capable of a limited rocking movement. On the operative stroke of handle 20, (the operative finger bars having been already moved forward until the rear edges of slots 150 are close up against bar 151), the pin 156 moves rearwardly in slot 153 whereupon spring 155 raises the rear end of bar 152 so that the pin is housed in the bottom of the vertical slot 154. On the reverse motion of lever 20, the arm 152 is moved forwardly by the pin 156, setting back all the finger bars and the bars operating the auto-bars to their normal position. As the link 152 reaches the end of its return stroke, roller 159 engages the inclined face of lug 158 depressing the rear end of arm 152 so that the pin 156 moves to the top of slot 154, whereupon spring 155 retracts the arm 152 again to the position illustrated in Fig. 7. This operation resets all the selector bars, and grids H, J, which have been moved. Rod 120 is also reset, if necessary, by its lever M¹. The ejector levers are also reset by the lugs 13b, Fig. 4, on the ejector hooks.

Shaft 16, Fig. 7, carries a pair of downwardly extending arms 16a coupled to a pair of links 161 coupled in their turn to bell-crank levers 162 rocking about fixed pivots 163 and supporting at their forward ends blocks 165, Fig. 5, connected to a plate 166 extending beneath the finger keys and through which all the finger key stems pass. The plate carries a pair of upwardly-extending arms 167, Figs. 4 and 7, whose upper ends are slotted and which are provided with a pair of cam faces 168 on each side of the slot. The bars T¹ that operate the setting of the finger keys extend forwardly through the slots and are provided with laterally-

arranged pins carrying rollers facing the cam faces 168. On the forward or operative stroke of handle 20, the levers 162 are rocked by the link 161 and the plate 166 is raised and engages pins 169 extending laterally from the finger key stems and adapted to be positioned when the finger keys are depressed close above the upper surface of plate 166. The forward stroke of lever 20 thus elevates all the finger keys which have been depressed, to their normal position. At the same time cam faces 168 move inwardly the bars T¹ which as shown in Fig. 3 are cranked to engage the outer ends of bars T. Thus, both bars T and T¹ are reset and the cams 38 are moved back to their idle or inoperative position with regard to finger bars 50.

The return stroke of bars T, T¹ resets shafts 34, 34a and levers M¹ and stops M; auto-bar link 70 at the same time resets grid F. The inhibitor bars are reset by means of lugs 180, Fig. 8, carried by each bar and engaged by a transverse rod 181 carried by a pair of links 182 rigid with a shaft 183 and rocked during the return stroke of bars T¹ by means of lugs 184, Fig. 6, engaging tails 185, Fig. 8, on the shaft 183.

The coin tubes O are arranged telescopically and an indicator O³, Fig. 3, may be arranged to lift above the top of the machine when a coin tube is empty. Alternatively a bell may be rung.

As previously stated, it is an important feature of the invention that the change-paying machine can readily be caused to actuate cash registering mechanism, and it is for this purpose that the finger keys are normally disconnected from the change-paying mechanism and are only operatively-connected thereto after a tender stop has been depressed.

Where the tender is equal to the amount of the change no tender stop is operated, the finger keys solely being depressed to operate the cash register.

In Figs. 1 and 2 I illustrate usual forms of Veeder mechanism 206 which may be actuated in known manner by swinging bars 201, 202, 203 and 204 extending beneath the finger key stems and operated by suitable feet 205 attached to the finger key stems, some of these being indicated in Figs. 1 and 2. A counter is indicated at 206, Fig. 1, driven by a toothed sector 207 operated from bar 201.

Owing to the weight of metal requiring to be moved when the change-paying mechanism is actuated, it may be necessary to render the Veeder mechanism dead beat, and for this purpose I may provide a special mechanism illustrated in Figs. 20, 21, 22, 23. Figs. 20 and 21 illustrate the actuating mechanism beneath the farthings keys in which is provided a shaft 220 adapted to be rotated

by the depression of either of three arms 221, 222, 223. The strokes of the arms 221, 222, 223 are limited by the baseplate of the machine. The arm 221 is coupled to the shaft 220 by a pin and slot mechanism providing a lost motion for two-thirds of the stroke, and the arm 222 is coupled to the shaft 220 by a pin and slot mechanism giving a lost motion for one-third of its stroke. Thus, 10 if arm 223 rotates shaft 220 by an amount causing the Veeder to register $\frac{3}{4}d.$, arm 222 will cause it to register $\frac{1}{2}d.$, and arm 221 $\frac{1}{4}d.$

The Veeder counter is operated by a usual pinion 230, Figs. 22 and 23 rigid with a ratchet plate 231 carrying a pawl 232 engaging a ratchet wheel 233 which operates the Veeder counter. A stop wheel 234 is provided behind the ratchet wheel 233 and connected to it, and its teeth are engaged by rollers 235 carried by pivoted arms 236 urged towards each other by a spring 237. It will be seen that as soon as the drive of the pawl 232 is taken off the ratchet 233 the rollers 235 will enter between adjacent teeth of the stop wheel 234 and render the actual Veeder mechanism dead beat.

Additional cash register mechanism for purchases exceeding £1. is indicated at 208 in Figs. 1 and 2. The change-paying mechanism does not operate in conjunction with this device in the model illustrated, but if a £5 note is tendered for a sale exceeding £1, the number of complete pounds in the change 35 should first be given separately, and the number of complete pounds in the sale separately registered on one of the special cash register stops. The remaining broken change of shillings and pence can then be operated 40 and the amount registered by the machine in the ordinary way.

A preferred embodiment of printing and receipt giving mechanism is illustrated in Fig. 26. In this figure the stems of the keys N are provided with lugs n^5, n^6, n^7, n^8 and n^9 adapted when the sales keys are depressed to rock bell-crank levers m^1, m^2, m^3, m^4 operatively connected to type bars n^{10} .

50 It will be understood that there is a row of levers in each case except m^4 , one lever being provided for each sales key in each row. The lugs n^7, n^8 of oppositely arranged sales keys of the shillings rows are arranged 55 both to operate the third row of bell-crank levers m^3 , a lug n^9 on the sales keys from 10/- to 19/- of the fourth row additionally operating a single bell-crank lever m^4 through an arm m^5 , when one of these keys is depressed, to actuate a type bar which adds the Figure 1, representing the 10/-, in front of the units digit imprinted by the lugs n^8 of the sales keys of the fourth row. The various bell-crank levers are connected to the type bars n^{10} through links n^{11} (of which only a

few are indicated for the sake of clearness) and in certain cases through the intermediary of additional bell-crank levers mounted on shafts n^{12} secured to the machine frame, these intermediate bell-crank levers being necessary in order that the connections from the sales keys (which extend across the whole width of the machine) may be communicated to the type arena (where the type bars are pivoted close together) without the links 70 fouling each other as will be readily understood.

As the operation of the type bars from sales keys stems is not new per se but has previously been described in my earlier British patent specification No. 221,654, the system of links and bell-crank levers need no further description.

The printing is effected on a strip of perforated paper V carried by a roll V¹ having rows of perforations and adapted to be fed forward one step at a time by teeth V² on a feed roll V³. A date-printing roll V⁴ is mounted on a spindle engaged by a slot V⁵ in a sector V⁶ adapted to be operated when lever 20 is operated through the intermediary of links 17a, 17b connected to shaft 17. When the sector V⁶ is moved, a drum V⁷ carrying a series of teeth V⁸ adapted to engage in the perforations of the paper strip V is also rotated, and a lever V⁹ rotates the drum V⁷ through the intermediary of a pawl W. The slot V⁵ is arcuate at its upper end 90 but moves inwardly towards its centre of rotation at its lower end.

The normal position of the links 17a when the machine is at rest is as shown in dotted lines. In this position the date-printing roller V⁴ is moved to the right and held on to the paper by the slot V⁵, and the teeth V⁸ of the drum V⁷ are moved round past their point of engagement with the perforations of the printed slip as will appear below.

When the keys N are depressed the amounts of the keys are printed on the paper by the type bar n^{10} . On the operative stroke of the handle 20, the link 17a rocks to the position shown in full lines, whereupon the slot V⁵ moves the roller V⁴ away from the paper and the teeth V⁸ move back to the position shown. The printed element of paper V is simultaneously fed down by the pawl W. On the return stroke of the lever, the date printing roller V⁴ is again moved forward by the slot V⁵ so as to print the date on that portion of paper next about to be used, and holds the upper strip fixed whilst the teeth V⁸ are rotated to the left and engage in the perforations above the strip of paper last printed 110 and tear it off so that it falls along a chute Z leading into chute Q as will be readily understood. The lever V⁹ is slotted at V¹⁰ to allow the necessary lost motion so that the feed roll will not begin to operate until 120 125 130

the date printing roll has moved away from the paper.

The machine as described will give the correct change on depressing the tender stop 5 for the smallest coin tendered for most combinations of English coinage. The following exception, however should be noted:

(1) If two half-pennies are tendered for a three-farthings sale, the 1d. tender stop 10 is depressed. This is to avoid the necessity of providing an additional stop for ½d. tender.

(2) If a half-crown or an odd number of half-crowns are tendered together with a 15 florin, one of the following two courses is possible:-

(a) Register 2/- on the cash register, the change-giving mechanism being idle; deduct 2/- from the amount of the sale and operate finger keys for the balance after depressing the odd half-crowns tender stop.

(b) Register the amount of the odd half-crowns on the cash register and deduct this amount from the sale, depressing finger keys 25 for the balance after operating the florin stop.

The course (a) is recommended, as deducting a florin is an easier mental process.

(3) When even half-crowns are tendered 30 together with a florin, either the even half-crowns should be registered on the cash register and the corresponding amount deducted from the sale, the sales keys for the balance being depressed after actuating the florins tender stop, or of course the process could be reversed and the florins deducted from the sale and the even half-crowns tender stop operated to throw out change for the balance.

(4) If a five-shilling piece is tendered 40 with a florin, the steps described in (2) or (3) should be taken. The reason for this is that grid J throws out the automatic shilling on a tender of a florin when the sales key for an even number of shillings is depressed. If, however, the florin is tendered 45 with a 5/- coin, the automatic shilling will be required when a sales key for an odd number of shillings is depressed, and as a 5/- coin is nearly, if not actually, obsolete, I prefer to leave the present arrangement as it 50 stands rather than introduce further complexity in the stop and key mechanism.

(5) If a four-shilling piece is tendered for a sale of less than 2/-, an extra florin must be given with the change ejected from the machine on depressing the florins stop. Here again, the 4/- coin is practically obsolete and the risk of this occurrence is insufficient to justify the provision of a special stop.

60 It is to be observed, however, that the machine as already described can clearly be extended by providing additional stops to meet the contingencies just described, but as stated, I prefer to leave it in its present form rather than introduce further mechanisms 65 for contingencies that are rare.

Obviously the machine could be made in smaller models working for example up to a maximum tender of half-a-crown in cases such as at certain railway stations or sports grounds where usually only small sums are paid and the proportion of 10/- and £1. notes tendered is small. In this case, obviously the machine would be much simplified and it is to be understood that such simplified models are included within the present invention in so far as they fall within the scope of the appended claims.

In particular it might frequently be found that the time taken in filling the note clips was not justified by the number of £1. notes tendered, in which case the machine would be arranged to operate up to a maximum tender of 10/-, tenders and/or sales higher than this amount being dealt within two operations as above described, 10/- extra change being paid separately or alternatively 10/- being separately registered on the cash register.

The adaptation of the machine to other systems of coinage will be readily apparent to those skilled in the art.

I claim:-

1. In a change-paying machine of the subtracting type, sales keys, a plurality of tender stops for selected values, the highest tender stop representing a value of at least one hundred times the amount of the smallest sales key and means to set the machine to give correct change in respect of plurality of tenders on actuating a single tender stop and keys to the amount of the sale.

2. In a changing-paying machine of the subtracting type, sales keys, a plurality of tender stops for selected values, and means to set the machine to give correct change in respect of a given tender on actuation of the tender stop for the smallest of a plurality of coins tendered, and of keys to the amount of the sale.

3. Universal change-paying machine of the subtracting type, tender stops for selected values, the highest tender stop representing a value of at least one hundred times the amount of the smallest sales key, a range of sales keys operable in accordance with exact sales amounts, and means whereby the machine is set to give correct change for substantially all transactions up to maximum tender by depressing a single tender stop and keys for the the amount of the sale.

4. Change-paying machine of the subtracting type, tender stops for selected values, a range of sales keys operable in accordance with exact sales amounts, and means whereby the machine is set to give correct change on depressing a tender stop for the amount of the smallest of a plurality of coins tendered, and keys for the amount of the sale.

5. In a change-paying machine, sales keys, ejector elements controlled by the sales keys,

- an element movable by any of the sales keys of one denomination of coinage, a second element movable by any of the sales keys of another denomination of coinage, means to inhibit an ejector element from being actuated when the two said elements are moved concurrently, and a rocker operatively engageable with the two said elements and said inhibiting means through the intermediary of two articulated joints and a pair of abutting faces. 5
6. Change-paying machine of the subtracting type having a tender stop for tenders of even numbers of a given coin and a second tender stop for odd numbers of the same coin, sales keys, ejectors normally uncoupled from said keys, said tender stops being adapted for alternative use to selectively couple said ejector devices to said sales keys 10 in alternative combinations. 15
7. In a change-paying machine of the subtracting type, a tender stop, sales keys covering the range of coin values up to that of said stop, monetary holding devices, ejector devices and means to set the machine to give change for any sales amount below the value of said stop, a second stop of lower value than the first mentioned stop and means for inhibiting the higher values of the holding devices without interfering with the capability of the remaining holding devices to give correct change for any sales amount below the value of said second stop. 25
8. In a change-paying machine of the subtracting type combined with a cash register and having tender stops, sales keys normally disconnected from the change paying mechanism, said keys being connected for operating the cash register and means to operatively connect the change-paying mechanism additionally to the sales keys when any tender stop is actuated. 30
9. In a change-paying machine, a row of sales keys carried on stems and adapted to be depressed, cams arranged relative to said stems, inhibitor devices, and movable devices actuated by said cams to contingently operate said inhibitor devices. 45
10. In a change-paying machine of the subtracting type, a tender stop, a row of sales keys carried on stems, cams arranged relative to selected sales keys, inhibitors, movable devices normally free of said cams, means to move said devices when said tender stop is actuated so that they lie in the paths of said cams, and means whereby said devices are thereafter further moved to operate said inhibitor when said selected keys are thereafter operated. 55
11. In a change-paying machine of the subtracting type, sales keys normally adapted to arm ejector devices for predetermined amounts of change, means to eliminate unity of a denomination when sales keys of two denominations are operated together, tender 60
- stops and means to supplementarily set an ejector device for said eliminated unity of change when a predetermined tender stop is actuated. 70
12. In a change-paying machine of the subtracting type, ejector devices, tender stops, and a range of sales keys normally disconnected from said ejected devices, the sales keys having a range from the lowest coin value up to the maximum unit of exchange, means for connecting all of said sales keys to the ejector devices on operation of certain of the tender stops and for connecting a lesser number of sales keys to the ejector devices when other tender stops are actuated. 75
13. In a change-paying machines of the subtracting type, a plurality of ejector devices for coin or note tubes, sales keys to operate said ejector devices, the range of sales keys extending from the lowest coin value to the maximum unit of exchange, operating means between said sales keys and said ejector devices, tender stops to couple said operating means for all of said sales keys and other tender stops to arm the operating means of selected sales keys only. 80
14. In a change-paying machine having tender stops, coin or note ejectors and an operating handle, sales keys having a value range extending from the lowest coin value to the maximum unit of exchange, coupling means whereby all sales keys are normally operatively disconnected from the coin ejectors and are only operatively connected thereto when a tender stop has been operated. 85
15. In a change-paying machine having tender stops, sales keys, coin or note ejectors and an operating handle, sales keys having a value range extending from the lowest coin value to the maximum unit of exchange, the provision of a plurality of coupling devices between all sales keys and a coin ejector, one of said devices being coupled only after a tender stop has been operated so that the machine cannot otherwise eject change. 90
16. In a coin-paying machine, coin ejectors, coupling therefor, sales keys to set couplings to said coin ejectors for amounts which are the complements of the amounts of the sales keys, tender stops for units of denominations which are inoperative on the amounts of ejectors set by sales keys, other tender stops which contingently set couplings for amounts additional to the amounts of the ejectors set by the sales keys, and other tender stops to inhibit certain of the ejectors from being coupled by certain of the sales keys. 100
17. In a change-paying machine of the subtracting type, sales keys, a tender stop for a value greater than unity of a denomination, a range of sales keys normally couplable to set ejector devices for predetermined amounts of change, and means whereby depression of said stop sets ejectors to throw out two given coins and actuates a coupling 105

device whereby certain selected sales keys are thereafter adapted to inhibit one of said ejectors.

18. In a change-paying machine, a rocker, a link articulated thereto about a pivotal axis, means normally to rock said rocker idly about said axis, means selectively movable to place an abutment in the path of said idle movement to partly obstruct it whereby to cause said rocking movement to displace said pivotal axis to positively displace said link.

19. Means as claimed in claim 18, in which said abutment has a plurality of normal settings for alternative use so as to give said link alternative displacements of different ranges.

20. In a change-paying machine, a coin ejector, a rocker pivoted to a movable element, an abutment mounted on a second movable element, means pivoted to said rocker selectively to determine the operation of said ejector, all so arranged that the operation of the ejector on movement of the first mentioned element is varied according to the setting of the abutment member carried by the second movable element.

21. Means as claimed in claim 20, in which the abutment member is capable of two operative settings so that three variations of ejector operations are possible.

22. In a change-paying machine of the subtracting type having tender stops, sales keys, and coin ejector devices, means whereby depression of a selected tender stop sets ejectors for certain coins, means whereby depression of a selected sales key sets ejectors for certain other coins, and means whereby all of said coins can be ejected simultaneously.

23. Means as claimed in claim 22, in which depression of a different sales key operates mechanism to set some or all of the same ejectors as the first sales key but additionally operates an inhibitor to unset the ejector set by the tender stop.

24. Change-paying machine of the subtracting type having tender stops, sales keys, and coin ejector devices, and having in combination means whereby a selected tender stop sets ejectors to deliver a predetermined amount of change, and means whereby a selected sales key sets ejectors to deliver a predetermined amount of change additionally to that of the tender stop.

25. A range of sales keys for odd and even multiples of a coin of a predetermined value, a tender stop, means whereby an ejector is set to deliver a coin of the said value by depression of said tender stop, means whereby a further ejector is set to deliver a further coin of the said value by the depression of a sales key for an even multiple of said coin, but not for an odd multiple of said coin.

26. In a change-paying machine, a range of tender stops, a plurality of ejectors, a

range of sales keys, all of said sales keys being normally disconnected from said ejectors but being selectively coupled thereto on depression of a tender stop.

27. A change-paying machine having a range of tender stops, a plurality of ejectors, a range of sales keys; a cash register mechanism, means whereby depression of any sales key normally operates said cash register mechanism but the ejectors only eject coin when a tender stop has been depressed prior to the depression of one of said sales keys.

In testimony whereof I affix my signature.

CHARLES LAURENCE BURDICK.
